UNITED STATES PATENT OFFICE.

JOSEPH H. WHEELER, OF CHICAGO, ILLINOIS.

HARNESS-SADDLE.

SPECIFICATION forming part of Letters Patent No. 644,838, dated March 6, 1900.

Application filed October 2, 1899. Serial No. 732,289. (No model.)

To all whom it may concern:

Be it known that I, JOSEPH H. WHEELER, a citizen of the United States, and a resident of Chicago, county of Cook, and State of Illinois, have invented certain new and useful Improvements in Harness-Saddles, of which the following is a specification, and which are illustrated in the accompanying drawings, forming a part thereof.

10 The invention relates to the saddle-piece of harnesses, and is particularly adapted for use in connection with heavy draft-harnesses, though it may be used in connection with lighter makes.

15 The object of the invention is to provide means for adjusting the pads of the saddle-piece up and down in order to better adapt them to the form of the animal's back and to give relief if the back becomes tender.

20 The invention consists in various parts and arrangement of parts hereinafter set forth, and illustrated in the accompanying drawings, in which—

25 Figure 1 is a detail plan of the improved saddle-piece, one of the pads being removed for the purpose of better showing the construction of the jockey-plate. Fig. 2 is a side elevation of the same. Fig. 3 is a detail longitudinal central section through one of the 30 pads and its jockey-plate. Fig. 4 is a plan view of the jockey-plate removed. Fig. 5 is a bottom plan of the same. Fig. 6 is a plan view of a hinge-plate used in connection with the pad. Fig. 7 is an end elevation of the 35 same. Fig. 8 is a plan view of a modified form of hinge-plate, and Fig. 9 is an end elevation of the same.

One of the pads of the saddle-piece is shown 40 at 10, and the jockey-plates, adapted to be attached to the pads, are shown at 11 11, the two jockey-plates being united by means of a rigid arch 12. Each jockey-plate is provided at its upper end with a downwardly and forwardly projecting lip 13, which is adapted to 45 pass through the outer cover 14 of the pad and through the reinforcing bur-piece 14^a. As the bur-piece is usually made of a composition which, while being quite hard, is liable nevertheless to become indented by continued pressure, the wear-plate 15 is inter-

posed between it and the lateral projection of the lip 13. The lower end of the jockey-plate is secured by means of screws, as shown. The under face of the jockey-plate is transversely recessed intermediate of its ends to 55 accommodate a hinge-plate 16, which carries the hinge-lugs 17, to which the arch 12 is pivotally secured. The width of the plate 16 is less than the length of the recess within which it is located, so that it may be adjusted longitudinally as to the jockey-plate, thereby providing for the adjustment of the pad longitudinally. In order to bind the hinge-plate in the position to which it may be adjusted, a binding-screw 18 enters it through a longitudinal slot 19 in the jockey-plate, and the contacting faces of the latter plate and the hinge-plate are serrated transversely as to the pad, as shown at 20 and 21.

To adapt the device for light harnesses but one hinge-lug is required, and hence the hinge-plate takes the form shown at 22, which is provided with a single upstanding hinge-lug 23, adapted to project through the slot 19.

Bumpers 25 are located at the upper end of 75 the jockey-plate, so as to receive the pressure of the arch 12 when the pad is tilted so as to raise its upper end, a movement due to the application of additional strain downwardly upon the pad, as by the driver stepping upon the shaft in mounting or alighting from the vehicle. These bumpers may take 80 any suitable elastic form. As shown they consist of blocks of rubber set in sockets formed in ears 24, projecting forwardly from 85 the jockey-plates.

In fitting the harness to a horse the pads may be adjusted to adapt them to the conformation of his back by simply loosening the binding-screws 18 and adjusting the hinge-plate relative as to the pad. Should the animal's back become tender, the position may be shifted in a similar manner, so as to give him relief, and inasmuch as the adjustment is accomplished so readily it will be found 90 advisable to shift the pads frequently.

I claim as my invention—

1. In a harness-saddle, in combination, a jockey-plate attached to the pad and having its lower face transversely recessed, a plate 100

fitting within such recess and adapted for movement longitudinally as to the pad, such plate having a hinge-lug, and means for securing the plate in any position to which it 5 may be adjusted.

2. In a harness-saddle, in combination, a jockey-plate attached to the pad and having its lower face transversely recessed and longitudinally slotted; a plate fitting within 10 such recess and adapted for movement longitudinally as to the pad, such plate having an upstanding hinge-lug, and a binding-screw

set through the slot of the jockey-plate into the hinge-plate.

3. In a harness, in combination, a pair of 15 pads, a jockey-plate attached to each pad and having a forwardly-projecting apertured ear, a rubber bumper secured in the aperture of the ear, and a rigid arch hinged to the jockey-plates so as to be cushioned by the bumpers. 20

JOSEPH H. WHEELER.
